UNITED STATES PATENT OFFICE.

CHARLES TUCKFIELD, OF EAST MOLESEY, ENGLAND, ASSIGNOR OF TWO-THIRDS TO DYSON WESTON, OF LONDON, ENGLAND.

ROTARY ENGINE.

SPECIFICATION forming part of Letters Patent No. 703,679, dated July 1, 1902.

Application filed November 15, 1901. Serial No. 82,389. (No model.)

To all whom it may concern:

Be it known that I, CHARLES TUCKFIELD, a subject of the King of Great Britain, residing at 12 Palace Crescent, East Molesey, Surrey, England, have invented new and useful Improvements in Rotary Engines, of which the following is a specification.

This invention relates to improvements in rotary engines.

According to the invention I provide a casing having a circular recess in which is fitted a disk keyed upon a shaft or spindle rotatably mounted in the casing. The disk is provided with one or more annular grooves upon both of its lateral faces, the said groove or grooves being, however, stopped at one or more points. In conjunction with each groove there is arranged a sliding abutment which is held in a recess in the casing and is caused to project into the groove by suitable means, such as by spring-pressure. Steam inlet and exhaust ports are provided on either side of the sliding abutment, and when steam is admitted it exerts pressure upon the stop in the groove and the sliding abutment and rotates the disk in the circular recess.

My invention is applicable to high-pressure motors and also to compound engines.

In the accompanying drawings, Figure 1 is a side elevation, partly in section, of a high-pressure rotary motor made according to the invention. Fig. 2 is a longitudinal section on the line 2 2, Fig. 1. Fig. 3 is a section on the line 3 3, Fig. 1. Fig. 4 is an elevation of the disk. Fig. 5 is a developed section on the line 5 5, Fig. 4. Fig. 6 is a sectional elevation of a compound rotary motor made according to the invention. Fig. 7 is a section on the line 7 7, Fig. 6. Fig. 8 is a section on the line 8 8, Fig. 6. Fig. 9 is an elevation of the disk. Fig. 10 is a view of a modified detail.

Referring first to the motor illustrated in Figs. 1 to 5, *a* is the casing, having the circular recess *a'*, and *b* is the disk which fits in the said recess *a'* and is keyed upon the shaft or spindle *c*, rotatably mounted in the casing *a*.

d is the annular groove which is formed in each face of the disk, and *e* is the stop which is provided in the groove, the said stop not having its sides perpendicular to the bottom

of the groove, but inclined or gradually sloping toward the said bottom, as shown at *e' e'*, Figs. 4 and 5.

f is the abutment provided in connection with each groove *d*, the said abutment being housed in a recess *f'* in the casing *a* and having a stem *f''*, which passes through a stuffing-box *g* in the said casing. Each abutment is held projecting into its groove *d* by a spring *f'''*, coiled around its stem *f''*, the said spring bearing at one end against the outer end of the abutment and at the other end against the stuffing-box *g*, as shown in Fig. 2.

h h are the steam-inlet ports, and *i i* the steam-exhaust ports, the latter of which open directly into the grooves *d*. The inlet-ports *h* open into the circular recess *a'* in the casing, and each port can be brought into communication with its groove by means of the recess *j*, formed in the central solid part of the disk *b*. This recess *j* is formed concentrically with the shaft and at the same distance from the center thereof as the point at which the port *h* opens into the recess *a'*, whereby as the disk rotates steam can flow into the recess *j* and thence through a hole *j'* into the groove *d* between the stop *e* and the sliding abutment *f*.

The operation of the motor is as follows: Assume the disk *b* to be in the position shown in the drawings. A recess *j* is just uncovering the inlet-port *h* on each face of the disk, so that steam enters each groove *d*, as shown by the arrow 1, Fig. 1, between the stop *e* and the sliding abutment *f*, thereby causing the disk to rotate. As the disk rotates the rear ends of the recesses *j j* cut off the steam admission and the disk is driven by the expansion of the steam, which escapes through the ports *i i*, as shown by the arrow 2, as soon as the stop *e* has passed the opening of this port.

The motor shown in Figs. 6 to 9 is similar to that above described, but is compound, the steam exhausting from the grooves *d d* into larger grooves *l l*, concentric with the grooves *d d*, and provided with stops *l' l'*. Furthermore, in the arrangement illustrated the admission of steam is not cut off to the inner grooves *d d*, as above described, the ports *h h* opening directly into these grooves. The exhaust-openings *i i* from the grooves

d d form the inlet-ports for the grooves *ll*, which are provided with exhaust-ports *m m* in the casing *a*. The steam takes the course shown by the arrows, Fig. 6—that is to say, it first enters the groove *d*, acts against the stops *ee*, and forces around the disk *b*, escapes through the port *i*, enters the groove *l*, acts against the stops *l' l'*, and finally escapes through the ports *m m*. The sliding abutments are in this case shown held in the grooves by the pressure of steam behind them instead of by springs, the steam being supplied by the passages *n n*. In this arrangement I have shown packing-rings *oo* pressed against the faces of the disk *b* by springs *pp* to prevent escape of steam from the grooves *d* and *l*.

Instead of employing steam-pressure to hold the abutments *ff* in the grooves *d* and *l* 20 I can connect their stems together by levers *qq*, as shown in Fig. 10, the levers being fulcrumed to pillars *rr* on the casing *a*. The grooves *d* and *l* are also made of the same depth, and the inclines *e' e'* extend nearly one 25 hundred and eighty degrees, so that the machines in one groove act upon the abutment therein to force the abutment in the other groove into contact with the bottom thereof.

Although I have in the above description 30 described the grooves as formed in the disk and the sliding abutments as held in the casing, it will be clear that this arrangement can be reversed, the grooves being made in the casing and the sliding abutments being held 35 in the disk.

Having now particularly described and ascertained the nature of my said invention and in what manner the same is to be performed, I declare that what I claim is—

40 1. In a rotary engine, the combination with a casing provided with a circular recess, of a disk located in said recess, a shaft secured to said disk, said disk being provided on a lateral face, with an annular groove, decreasing

gradually in radial diameter from the face of 45 the disk, and a stop in said groove, having an inclined face extending from the face of the disk to the bottom of said groove, and a sliding abutment mounted in the casing and fitting said groove, substantially as described. 50

2. In a rotary engine, the combination with the casing provided with a circular recess and inlet and exhaust ports, of a rotary disk mounted therein and having a lateral face provided with an annular groove, a stop located 55 in said groove, a cut-off recess communicating with said groove, and constructed to communicate with the inlet-port and a sliding abutment mounted in said casing and fitting said groove, substantially as described. 60

3. In a rotary engine, the combination with the casing provided with a circular recess and inlet and exhaust ports, of a rotary disk mounted therein and having a lateral face provided with an annular groove, a stop located 65 in said groove, a cut-off recess located in the hub of said disk, communicating with the said groove, and constructed to communicate with the inlet-port, and a sliding abutment mounted in said casing and fitting said groove, substantially as described. 70

4. In a rotary engine, the combination with the casing provided with a circular recess and inlet and exhaust ports, of a rotary disk mounted therein and having its lateral faces 75 provided each with an annular groove tapering gradually from the face of the disk to the bottom of the recess, a stop located in each groove and provided on each side with an inclined face extending from the lateral face of 80 the disk to the bottom of the recess, and sliding abutments mounted in the casing and fitting said grooves, substantially as described.

CHARLES TUCKFIELD.
